DOMESTIC APPLIANCE

Francis H. McCormick, Dayton, Ohio, assignor to
General Motors Corporation, Dayton, Ohio, a
corporation of Delaware

Application December 31, 1938, Serial No. 248,823

14 Claims. (Cl. 126—191)

This invention relates to a domestic appliance, and more particularly to doors and door controls for stoves and refrigerators.

The doors usually provided on stoves are supported on a hinge pin and provided with a balancing spring and some sort of a catch for holding the door closed. It has been customary to mount these control parts upon different portions of the adjacent stove structure. I have found that misalignment sometimes occurs when the stove is constructed in such a manner, resulting in difficult and undesirable door operation, and these parts are often difficult to assemble when mounted in this manner.

It is an object of my invention to provide a concealed construction for a door and door control which will prevent misalignment, facilitate assembly and provide convenient accessibility for the parts thereof.

It is a further object of my invention to provide a stove construction in which an assembly including the hinge pin bearing, the catch and the balancing spring is made as a unit and is assembled into the stove as a unit, thereby facilitating the assembly and insuring alignment of the door and door control.

It is another object of my invention to provide an improved balancing arrangement for a door of the type generally used on stoves.

It is still another object of my invention to provide a concealed door control construction for an oven in which the parts including the balancing spring, catch mechanism and door connections are readily accessible for adjustment and removal from the bottom of the stove or from a drawer compartment beneath the oven.

It is a further object of my invention to provide an improved concealed hinge type of door construction for a stove.

Further objects and advantages of the present invention will be apparent from the following description, reference being had to the accompanying drawings, wherein a preferred form of the present invention is clearly shown.

In the drawings:

Fig. 1 is a perspective view of an electric range embodying my invention;

Fig. 2 is a fragmentary sectional view of one front corner portion of the oven including a portion of the door taken along the line 2—2 of Fig. 3;

Fig. 3 is a sectional view of the unitary assembly incorporated in the range taken along the line 3—3 of Fig. 2;

Fig. 4 is a sectional view taken along the line 4—4 of Fig. 3;

Fig. 5 is a sectional view taken along the line 5—5 of Fig. 2; and

Fig. 6 is a sectional view taken along the line 6—6 of Fig. 3.

Fig. 7 is a view showing a vector analysis of the forces applied to the door.

Briefly, I have shown an electric range provided with a balancing spring door catch and hinge pin bearing in the form of a unitary assembly which may be assembled into the range as a unit prior to the attachment of the door and the lining of the oven. This assembly is fastened by screws to the door jamb portion of the shell so that all the parts cooperating with the door are thereby maintained in proper alignment and relationship. The connection between the door and its control, as well as the adjustment of the control, are both readily accessible from the drawer compartment beneath the oven.

Referring now to the drawings, and more particularly to Fig. 1, there is shown an electric range, generally designated by the reference character 20, provided with an outer shell 22 containing an oven compartment lined by the oven liner 24. The outer shell 22 is provided with an opening registering with the oven liner 24 and is provided with a recessed flange 26 around the opening which serves as the door jamb for the oven door 28. The flanged recess 26 is sufficiently deep to substantially entirely receive the oven door 28 so as to make the front face of the oven door substantially flush with the other portions of the shell 22. The door 28 is provided with an inner sheet metal member 32 having its edges 32 flanged forwardly, while an outer sheet metal member 34 has its edges 36 flanged in the opposite direction from the flanged edges 32 and overlapping the flanged edges 32. On either side of the door between the flanged edges 32 and 36, there is inserted a heavy metal hinge bracket 38 which is welded or otherwise bonded to the flanged edge 32. This hinge bracket 38 has a portion which extends along the flanged edge of the inner sheet metal member 32 to the bottom of the door. This portion of the bracket 38 is provided with an aperture adjacent the bottom of the door for supporting the hinge pin 40, which is provided with a flattened portion 42 at its inner end fastened to the inner face of the door by the screw 44. The flanged edge of the sheet metal inner member 32 along with the adjacent portion of the hinge bracket 38 is recessed inwardly from the flanged edge of

the outer sheet metal member 36 to provide a recess 46 in the lower corner of the inner face of the oven door.

This recess 46 receives a projecting arm 48 extending through a slot in the adjacent portion of the door jamb portion of the outer shell 22. This projecting arm 48 is provided with an aperture which receives the hinge pin 40 for pivotally connecting the door to the projecting arm 48. This provides a simple construction by which the hinge of the door is concealed, when the door is closed, and is comparatively unobjectionable when the door is open.

The hinge bracket 38 is also provided with an integral curved arm portion 50 which extends through a slot 52 in the door jamb portion of the outer shell. This curved arm 50 also extends through a slot registering with the slot 52. This second slot is formed in the front face 98 of the door catch bracket member 54, which is fastened by screws 56 to the rear of the door jamb portion of the outer shell. The projecting arm 48 is preferably welded, or otherwise secured, to one side of the bracket member 54.

The bracket member 54 is also provided with the balancing spring and the cam follower mechanism which cooperate with the curved arm 50. The balancing spring is in the form of a flat spiral spring 58, which has a tongue at its inner end held within a slot in the anchoring pin 60. This anchoring pin 60 is riveted to an adjusting arm 62 provided with an arc-shaped slot 64 by which the pin 60 and, thereby, the spiral spring 58, may be fastened at any angle desired within the limits of the slot 64 by the locking screw 66 which passes through both side portions of the bracket 54. The spiral spring 58 has its opposite end extended in the form of an arm 68 having a link 70 hooked into an aperture at its outer end. This link 70 is also provided with a hook at its upper end which is hooked through an aperture 72 in the arm 50.

The spring is so adjusted and the arm 68 and link 70 are so proportioned that when the door approaches closed position, the effective lever arm of the portion 68 of the spring 58 is shortened so as to increase the mechanical advantage of the spring so that in spite of the fact that the tension of the spring is reduced, the door will be held in the closed position by the tension of the spring through its greater mechanical advantage. As the door is opened, the tension of the spring is increased, but the effective lever arm is lengthened so that the force of the spring mechanism as applied to the door increases only gradually.

It should be noted that as the door moves further towards horizontal position, more force is required to balance its weight, because the portion of the weight of the door required to be balanced by the spring 58 is in proportion to the sine of the angle of the door opening. Thus, in the wide open position of the door, it is necessary that the force provided by the spring 58 be considerably increased. As the spring is stretched, it naturally increases considerably in tension. In addition, after the door is a little more than half way open, the effective lever arm is shortened, thereby increasing the mechanical advantage of the spring 58 so as to provide additional force for counter-balancing the door. Thus, by this arrangement, I am able to effectively counter-balance the weight of the door by the effective use of the two variables, namely, the tension of

the spring and the effective length of the lever arm.

Fig. 7 is a vector analysis of the force applied to door 28. The door, in its vertical position is indicated in dotted lines at 28. It fulcrums about the point 40 through the three positions 100, 100a and 100b. The spring 58 creates a force about the point 60, through the arm 68 to the point 110, where the arm 68 is attached to the link 70. The spring 58 creates a force tangential to the radius 111, which force is indicated by the vector 112. The force is assumed to equal four units. The link 70 is attached to the arm 50 at the aperture 72 and creates a pull on the arm 50 along the line 113. The force 112, by vector analysis, creates a pull along the line 113 equal to the distance from the point 110 to the point 114. This distance is marked off along the line 113 from the point 115 to the point 116. By vector analysis, this force is resolved along the line 117 tangentially to the radius 118, which radius 118 represents the force supplied to the arm 50 about the point 40. The force applied along the line 117 is equal to 7 and a fraction units and indicates the force applied to the door when in the fully closed position 110.

Assume now that the door is moved to position 100a. When this occurs, the point 110 moves to 110a and other points move to corresponding points similarly numbered with the suffix a added thereto. In this new position it will be seen that force 112, which corresponds to the spring has been increased due to the winding of the spring and is now indicated by the numeral 112a to be 5 and a fraction units in length. By vector analysis similar to that previously described, the force along line 117a is found to be only 5 and a fraction units, which is less than the force 117 previously described.

Assume that the door is then moved to its horizontal position 100b, and that the points of the vector analysis have now moved to positions indicated by numbers having the suffix b thereto attached. The point 115 has now moved to 115b and the point 110 has moved to the point 110b. The force of the spring along the line 117b is assumed to be 6 and a fraction units, because of the increased tension of the spring caused by winding the same about the point 60. By vector analysis similar to that previously described, it will be found that the force along the line 117b is now 6 and a fraction units, which is greater than the force 117a previously described.

From the above vector analysis it is evident that the torsional forces applied to the door 28 about the point 40 are greatest in positions 100 and 100b and are less at the position 100a. This permits the door to be held firmly closed in vertical position, and provides more power for counterbalancing the door as it reaches the horizontal position, where its moment about the point 40 becomes greater.

The foregoing vector analysis is intended to be only by way of example, and it is to be understood that the force of the spring and the distance creating the various vectors may be varied as desired, so long as the increased torsional forces are applied at the upper and lower positions of the door.

I do not rely upon the spring 58 for holding the door in tightly closed position. In order to hold the door in tightly closed position, I have provided the cam surfaces 74 and 76 upon the lower end of the arm 50. These cam surfaces 75 cooperate with the cam roller 78 rotatably sup-

ported on a bearing surrounding a screw 86 which is fastened at its opposite ends to a follower member 82 pivotally supported upon a pin 84 which, in turn, extends across and is supported by the side portions of the bracket member 54. The roller 78 is spring pressed into engagement with the cam surfaces 74 and 76 by a compression type coil spring 88 which extends between the spring seat 88 formed on the lower end of the pivoted bracket 82 and a spring seat 90 formed on the lower end of a bracket 92 which is spot-welded to the side portions of the bracket 54. A bolt 94 extends from one of the spring seats to the other through the inside of the coil spring 88 for limiting the outward movement of the cam roller 78. In this way, the cam roller 78 will only engage the cam portions 74 and 76 of the arm 58.

When the cam roller 78 is in engagement with the cam surface 74, it holds the door in tightly closed position. For broiling purposes, however, the door is pulled slightly open so that the spring 88 holds the door with the cam surface 76 in engagement with the cam roller 78. This holds the door slightly open so that vapors formed during broiling may escape from the oven. The force of the cam roller may be adjusted by changing the effective length of the bolt 94. The arm 58 is also provided with a shoulder 96 which is adapted to engage the rear face of the connecting front portion 88 of the bracket 54 to serve as a stop for limiting the opening movement of the door. Thus, it will be seen that the hinge bracket 38 including the arm 58 serves as a support for the hinge pin 48; it strengthens the lower portion of the door; it serves as a connection to the link 70 and spring 88; it also serves as a stop for limiting the opening movement of the door; and it also provides cam surfaces which cooperate with the cam roller 78 for holding the door tightly closed or slightly open for broiling purposes.

This construction provides for excellent alignment and ease of assembly. The bracket member 54, together with all its parts, is assembled prior to its installation in the oven. Thus, prior to its assembly into the oven, the bracket 54 is provided with the bracket 48, as well as the follower 82 and bracket 92, together with all their parts, as shown in Fig. 3, and also the spring 88, together with its anchoring pin, arm and screw. Before the oven liner is inserted, the hinge bracket 54 is put into its proper place from the rear of the door jamb portion 26, and fastened by the screws 86 which serves to locate the bracket 54 and all its parts, including the hinge pin bracket 48, the brackets 82 and 92, which control the cam roller and the spring 88. The door, through the bracket 48, is aligned with the bracket 54 and the door jamb portion 26 by the screws 86 which insure the location of the bracket 54. The arm 58 is located in the door with respect to the hinge pin which is aligned by the bracket 48 so that it is thereby properly aligned with the bracket 54 and, thereby, is aligned properly with the cam roller 78 and the spring 88.

After the bracket 54 is fastened in place, the oven liner is inserted and the door 58 is put into its proper place and the hinge pin 48 inserted in the bracket 48. At this time, the link 78 is connected to the arm 58 and the arm 68. This is easily done from the drawer compartment 102 provided immediately below the bottom wall 104 of the oven compartment which supports the insulation beneath the oven liner. This bottom wall 104 is notched to receive the bottom of the bracket 54. The aperture 72 is lo-

cated at the level of the bottom wall 104 and is sufficiently large so that the upper end of the link 78 can readily be hooked thereon from the drawer compartment 102. The lower end of the link 78 may readily be hooked to the end of the spring arm 68 which is obviously accessible. If desired, the adjusting screw 66 may be loosened to reduce the tension of the spring 68 to facilitate the connection. This adjusting screw 66 is also readily accessible within the drawer compartment as is the screw 94. Thus service calls desiring a change in the door control may readily be taken care of. It will, therefore, be seen that by this construction of the door and door control, all the parts may be properly aligned by simply assembling the bracket as above described. The bracket 54 is supported entirely by the three screws shown in Fig. 3.

While I have described this door and door construction as applying to an oven, it is also applicable to other uses of this type door which may be used for refrigerators and other forms of cabinets.

While the form of embodiment of the invention as herein disclosed, constitutes a preferred form, it is to be understood that other forms might be adopted, all coming within the scope of the claims which follow.

What is claimed is as follows:

1. In combination, a door jamb member, a door for closing the opening surrounded by the door jamb, a wall construction cooperating with said door jamb member, a supporting member constituting a separate element distinct from said wall construction and fastened to said door jamb member independently of said wall construction, an arm fastened to the door, spring means anchored to said supporting member and connected to said arm, and pivot means fastened to and extending from said supporting member for pivotally supporting said door.

2. In combination, a door jamb member, a door for closing the opening surrounded by the door jamb, a wall construction cooperating with said door jamb member, a supporting member constituting a separate element distinct from said wall construction and fastened to said door jamb member independently of said wall construction, an arm fastened to the door, spring means anchored to said supporting member and connected to said arm, said arm being provided with a cam surface, and a spring pressed cam roller supported by said supporting member and acting upon said cam surface of said arm for controlling the door.

3. In combination, a door jamb member, a door for closing the opening surrounded by the door jamb, a wall construction cooperating with said door jamb member, a supporting member constituting a separate element distinct from said wall construction and fastened to said door jamb member independently of said wall construction, an arm fastened to the door, a spirally wound spring means anchored to said supporting member, and link means connecting the free end of said spring means and said arm.

4. In combination, a door jamb member, a door for closing the opening surrounded by the door jamb, a wall construction cooperating with said door jamb member, a supporting member constituting a separate element distinct from said wall construction and fastened to said door jamb member independently of said wall construction, an arm fastened to the door, a spirally wound spring means anchored to said supporting mem-

ber, link means connecting the free end of said spring means and said arm, and means for adjusting the anchorage of said spring means.

5. In combination, a door jamb member surrounding an opening, a wall construction co-operating with said door jamb member, a door for closing said opening, said door being provided with an arm, said door jamb member having a slot for receiving said arm, a supporting member constituting a separate element distinct from said wall construction located behind said slot, fastening means extending through said door jamb member for fastening said supporting member to said door jamb member, spring means connecting said arm and said supporting member, said supporting member being provided with a projection extending through said door jamb member, and means for pivotally mounting said door upon said projection.

6. In combination, a door jamb member surrounding an opening, a door for closing said opening, said door being provided with an arm, said door jamb member having a slot for receiving said arm, a supporting member located behind said slot, fastening means extending through said door jamb member for fastening said supporting member to said door jamb member, spring means connecting said arm and said supporting member, said arm being provided with a cam surface, a cam roller pivotally mounted upon said supporting member, and spring means for holding said cam roller in engagement with said cam surface.

7. In combination, a door jamb member surrounding an opening, a door for closing said opening, said door being provided with an arm, said door jamb member having a slot for receiving said arm, a supporting member located behind said slot, fastening means extending through said door jamb member for fastening said supporting member to said door jamb member, a torsion spring anchored to said supporting member, said torsion spring being provided with an extending portion, and means connecting said extending portion and said arm.

8. In combination, a door jamb member surrounding an opening, a door for closing said opening, said door being provided with an arm, said door jamb member having a slot for receiving said arm, a supporting member located behind said slot, fastening means extending through said door jamb member for fastening said supporting member to said door jamb member, and spring means connecting said arm and said supporting member, said supporting member including two parallel portions extending rearwardly from said door jamb member, said spring means being located between said parallel portions.

9. In combination, a door jamb member surrounding a door opening, a door for closing said door opening, said door including an inner sheet metal member having its edges flanged in one

5 direction, an outer sheet metal member having its edges flanged in an opposite direction around said flanged edges of said inner sheet metal member, a bracket fastened between said flanged edges, a projection extending outwardly from said door jamb member and being pivotally connected to said bracket, the flanged edges of said inner sheet metal member being recessed inwardly away from the flanged edges of the outer sheet metal member for receiving said projection.
